CLAIM

The ornamental design for a candle holder, as shown and described.

DESCRIPTION

FIG. 1 is a front perspective view of a candle holder, illustrating my new design;

FIG. 2 is front elevational view;

FIG. 3 is a rear elevational view;

FIG. 4 is a left elevational view;

FIG. 5 is a right elevational view;

FIG. 6 is a top plan view; and,

FIG. 7 is a bottom plan view.

The broken lines in the figures are for the purpose of illustrating portions of the candle holder and form no part of the claimed design.
